STEAM GENERATING APPLIANCE FOR REMOVING WRINKLES FROM CLOTH ARTICLES

Alfred W. Madl, Glendale, Wis., and John M. Kupiec, Brooklyn, N.Y., assignors to John Oster Manufacturing Co., Milwaukee, Wis.

Filed May 6, 1970, Ser. No. 22,831

Term of patent 14 years

Int. Cl. D15—05; D23—99

U.S. Cl. D49—13

Fig. 1.

Fig. 2.

Fig. 3.

Fig. 4.

Fig. 5.

Fig. 6.

FIG. 1 is a perspective view of a steam generating appliance for removing wrinkles from cloth articles embodying our new design;

FIG. 2 is a front elevational view thereof;

FIG. 3 is a left side elevational view thereof;

FIG. 4 is a top plan view thereof;

FIG. 5 is a bottom plan view thereof; and

FIG. 6 is a rear elevational view thereof.

We claim:

The ornamental design for a steam generating appliance for removing wrinkles from cloth articles, as shown.
